UNITED STATES PATENT OFFICE.

HARRY C. LITTLE, OF MOUNT GILEAD, OHIO, ASSIGNOR TO THE HYDRAULIC PRESS MANUFACTURING COMPANY, OF MOUNT GILEAD, OHIO.

PUMP UNLOADER.

Application filed February 23, 1922. Serial No. 538,605.

To all whom it may concern:

Be it known that I, HARRY C. LITTLE, a citizen of the United States, and resident of Mount Gilead, in the county of Morrow and State of Ohio, have invented certain new and useful Improvements in Pump Unloaders, of which the following is a full, clear, and exact description.

When the suction check of any plunger pump is mechanically held out of its seat, the fluid which is drawn into the pump cylinder on the suction stroke is ejected back to the reservoir by the same passage by which it enters. In this way no delivery is secured from the pump. Whenever the suction check is allowed to come to rest on its seat, the delivery from the pump begins immediately. Ordinarily the suction check is lowered on to its seat at any time the controlling mechanism permits. This gives a satisfactory action if the check is lowered at about the end of the suction stroke so that the load is picked up by the pump in a gradual manner. If, however, the check happens to be lowered onto its seat during the regular discharge stroke of the pump, the full load is often thrown upon the pump suddenly by beginning the delivery at the point of greatest discharge. This often results in the breakage of the check, the gears or even the pump frame.

An object of my invention is to provide means whereby the check is closed only at about the end of the suction stroke no matter at what point in the operation the controlling mechanism may release the same.

Another object is to provide a simple and efficient device for producing this result which is controlled by the movement of the pump itself through some reciprocating part thereof.

Other objects will be apparent from the following detailed description and the appended claims.

45 In the drawings:

Figure 1 is a side elevation with parts in section and parts shown diagrammatically, the check valve being closed.

Figure 2 is a sectional view on a larger scale showing the check valve held open.

The gear A and pitman B may represent any desired means for giving a reciprocatory movement to the pump piston 1. The usual cross-head 2 and shoe 3 are illustrated and are normally fastened together to move

together in guides in the frame 4. In a portion of the pump casing 5 is the usual suction check valve 6 controlling the connection between the passageways 7 and 8. When this suction check is held open, the reciprocation of the pump piston obviously produces no delivery of fluid.

In the casing 5 is mounted to reciprocate a stem 9 which has packing 10 where it passes through the casing, and is provided with an enlargement 11. Engaging one side of this enlargement is a coiled spring 12 bearing at its other end against the casing 5 or packing 10. Engaging the other side of the enlargement 11 is a larger coiled spring 13 bearing at its other end against a stem 15 guided in a passageway 16 in a portion 17 of the casing. As clearly shown in Figure 2 there is a depression 14 in the upper end of the stem 15 in which the stem 9 has a limited amount of independent movement. The stem 15 has a groove 18 there-around not far from its upper end.

Adapted to engage with this groove when the stem 15 is raised, is a longitudinally sliding rod 19 having a sharp end 20 to engage the groove and an upturned end 20' at its opposite end. A spring 21 is arranged on the rod to force it into engagement with the groove 18 in the stem 15 whenever the latter is raised. The upturned end 21 of the rod 19 is engaged by the shoe 3 near the close of each suction stroke of the pump piston.

Pivoted at 22 is a lever 23 having one end 25 underlying the stem 15 and carrying a weight 24 adjacent its other end. This lever is connected in any desired manner with the accumulator or receiver, and as diagrammatically illustrated a rope or wire 26 fastened at one end to the lever 23 runs over pulleys 27 and 28 and supports a weight 29 at its other end, which weight is heavier than the weight 24.

This weight 29 is suspended over the movable part of an accumulator which is conventionally illustrated as comprising a fixed piston cylinder 31 whose piston lifts a movable part 30 carrying weights 32. The exact design of the accumulator is immaterial so far as my invention is concerned and therefore the accumulator and connections to the lever 23 have been merely outlined.

The operation of the device is as follows: Assuming the parts to be in the normal

position shown in Figure 1, the pump will operate in its usual manner until the accumulator piston reaches a predetermined point, when the weights 32 will be lifted into engagement with the weight 29 and raise it. This will permit the weight 24 to fall and move the lever 23 whose end 25 will lift the stem 15. If this takes place when the pump is on the discharge stroke the check valve will be held closed, and the upward movement of the stem 15 will compress the spring 13 after the stem 9 contacts with the check valve. When the pump plunger reaches the end of its stroke, the check valve will be free to rise, and the spring 13 will lift the stem 9 and check valve, placing the lighter spring 12 under compression. The relative movement above described between the stems 15 and 9 is permitted by the lost motion of the stem 9 in the opening 14 in the stem 15.

As soon as the check valve is thus raised, the stem 15 has reached a point where the end 20 of the rod 19 can engage in the groove 18 of the stem 15 and thus prevent the stem from dropping. At the end of each suction stroke the sliding shoe 3 will engage the end 20' of the rod 19 and move the end 20 out of engagement with the groove, but so long as the piston of the accumulator remains at the predetermined point, the lever 23 will hold the stem 15 up and the check valve open, and the rod 19 will immediately reengage in the groove.

Now when the piston of the accumulator has been lowered, the weight 29 descends raising the lighter weight 24 and moving the end 25 of the lever 23 down away from the stem 15. However, if this action takes place at any time except at the end of the suction stroke, the stem 15 will be retained in its upper position shown in Figure 2, holding the stem 9 in position to retain the check valve open because of the engagement of the end 20 of the rod 19 with the groove 18. Just as soon as the end of the suction stroke is reached the cross head and shoe 3 engage the end 20' of the rod and move the end 20 out of engagement with the groove 18, whereupon, as the spring 13 is released, the lighter spring 12 overcomes the packing friction and moves the stem 9 downwardly allowing the check valve 6 to close.

It is therefore apparent that the valve can only be closed at the end of the suction stroke irrespective of the point at which the controlling mechanism governed by the accumulator may function. The load therefore comes on the pump gradually from the beginning of the discharge stroke.

This invention has been illustrated in connection with an accumulator in which the pressure is constant, and the check valve is opened when the fluid discharge from the pump is in excess of the fluid drawn from

the lines, in order that the accumulator may not be overcharged. It is obvious however, that it might be used in connection with devices which depend upon an increase of pressure to open the check valve. Also, the lever 23 might be used to operate by means of a spring pressed valve similar to a pop valve, and the action of the pump would then be controlled by pressure instead of by the position of an accumulator piston.

The device has been illustrated in a horizontal pump, but it is obvious that it is not limited thereto but may be used in a vertical pump. It may also be used on a pump with more than one cylinder. The character of fluid placed under compression by the pump is also immaterial. In general it may be said that the invention is not limited except as recited in the appended claims.

I claim as my invention.

1. A pump unloader comprising a check valve, a receiver, means for holding the check valve open when the charge in the receiver has reached a predetermined point, and means for preventing the closing of said valve except near the end of the suction stroke of the pump.

2. A pump unloader comprising a check valve a receiver, means for opening said check valve when the charge in the receiver has reached a predetermined point, means for retaining the check valve in open position, and means for releasing said retaining means only near the end of the suction stroke of the pump.

3. A pump unloader comprising a check valve, means for opening said check valve when a predetermined charge is reached, means for retaining the check valve in open position while said charge is maintained, and means operated by a moving part of the pump for releasing said retaining means only near the end of the suction stroke of the pump.

4. A pump unloader comprising a check-valve, means for opening said check valve when a predetermined charge is reached, a detent for retaining said valve in open position, and means for moving said detent to inoperative position only near the end of the suction stroke of the pump.

5. A pump unloader comprising a check valve, means for opening the check valve under predetermined conditions, means for retaining the check valve in open position so long as said conditions exist, and means for releasing said retaining means and allowing the valve to close only near the end of the suction stroke of the pump.

6. A pump unloader comprising a check valve, means for opening said check valve when a predetermined charge is reached, a detent for retaining the check valve in open position except near the end of the suction stroke of the pump, and a sliding member

to engage and release the detent at that time.

7. A pump unloader comprising a check valve, a sliding stem for opening said valve when a predetermined charge is reached, another stem engaging the first stem, a detent engaging the second stem to hold it in the position it reaches after it has operated the first stem to open the valve, and means for releasing said detent only near the end of the suction stroke of the pump.

8. A pump unloader comprising a check valve, a sliding stem to engage said valve and open the same when a predetermined charge is reached, a second stem to operate the first stem, a detent engaging the second stem to hold it in operated position, and means engaged by a moving part of the pump to release said detent only near the end of the suction stroke of the pump.

9. A pump unloader for pumps having a reciprocating part, means for causing said part to reciprocate idly, and means for causing it to resume its normal function only near the end of the suction stroke of the pump.

10. In a pumping mechanism having an accumulator and a check valve, an unloader comprising means operated by an increase of the charge in the accumulator above a predetermined point for opening the check valve, means for retaining the valve open so long as said condition continues, and means for thereafter releasing said retaining means to allow the valve to close only near the end of a suction stroke of the pump.

In testimony whereof, I have hereunto subscribed my name.

HARRY C. LITTLE.
